PAPER CONTAINER

Filed Nov. 2, 1927

Inventor
E.C. Angell

By his Attorney *Wm. H. Reid*

UNITED STATES PATENT OFFICE

EDWARD C. ANGELL, OF NEW YORK, N. Y.

PAPER CONTAINER

Application filed November 2, 1927. Serial No. 230,409.

The present invention has reference to receptacles or containers formed of paper or the like material, wherein the container in the form of a somewhat cylindrical body is provided with a bottom in its manufacture or production, and when filled the container may be closed by a cap or cover in one mode of use, and in another use of the articles, the top is collapsed or pressed together and sealed by 10 a suitable clamping member such as a bent strip of metal.

The present invention relates particularly to a new arrangement of the lapped edges of the body, where a sheet or blank is bent or 15 rolled, and the edges or margins lapped and secured by a suitable adhesive such as glue.

One object of the present invention is to provide improved means for making the lap joint where the margins are caused to adhere 20 by the glue, in the form of flutes or corrugations, and which preferably extend longitudinally in the direction of the edges.

In the accompanying drawings showing 25 embodiments of my invention:

Fig. 1 is a side elevation of a container of the tapered form with the top collapsed and sealed.

Fig. 2 is a side elevation of the same.

Fig. 3 is a cross section.

30 Figs. 4 and 5 show different forms of the flutes.

Fig. 6 shows the container with cylindrical walls.

The container or receptacle is shown formed 35 of a body 2 which is a blank or sheet of paper that is bent to a tubular form, with the margins lapping as at 3 and 4. In Figs. 1-5 the blank is so formed that the tubular body will be of a conical form or tapered upwardly, after 40 the margins have been secured by lapping, with the suitable adhesive between the engaged faces. A bottom 5 is inserted and secured by suitable means or mechanism, such as rolling the edges of the blank and of the 45 flanged bottom member, which is well known in this art.

Where the flat blank is rolled to a tubular form, with the lapping edges that are secured by a suitable adhesive, the edge of the outer 50 margin has a tendency to move outwardly, to

remain in the former flat position. To insure a tight seal throughout the lapped margin, I have the lapped portions indented, or made of such form that they will tightly adhere. As shown in Figs. 1 and 3 I arrange flutes or corrugations extending longitudinally, in the direction of the edges, and which correspond in the two lapped portions, and are caused to register as indicated in Fig. 3. This is preferably done by pressing means engaging the inner and outer faces of the lapped portion, that will have a corrugated contour and thus force together these fluted portions with the interposed adhesive. This may be done by bringing together the lapped portions in the flat form of the blank, and two corrugated pressing members will thus form these corrugations at the same time that the lapped portions are brought together. In this art it is customary to wrap the blank around a mandrel with a suitable adhesive between the lapped edges, and then a plunger or presser is brought down to press the lapped edges against the mandrel. These members are 60 preferably provided with corrugated faces 65 that will produce the result set forth. In Fig. 4 a similar arrangement is shown in which the corrugations at 7 extend slightly inclined to the longitudinal edges, which obviously can be done by forming such corrugations in the pressing members. In Fig. 5 a similar arrangement is shown in which the corrugations or flutes at 8 extend in opposite directions and intersect.

In Fig. 6 a container is shown in which the tubular body form is cylindrical, instead of tapered. It is obvious that the same arrangement of corrugations can be formed in the lapping edges of the blank as set forth, in such a container, and in the same manner.

Where the containers are sealed by a bent strip as 9, after collapsing or pressing together the upper edges, and then applying and closing the strip, the corrugations are preferably omitted at the top and which terminate a short distance beyond this end of the container. This will make a better closing or seal by the bent strip. The same form of a cylindrical container is shown in Fig. 6, the corrugations terminating back of the open

end, and thus will not engage the flange of the usual cap.

What I claim is:

1. A paper receptacle including a body formed of a sheet of material shaped to tubular form and having its longitudinal edges lapping and provided on their confronting faces with adhesive, said lapping edges being corrugated with a series of narrow and equal 5 corrugations symmetrical on opposite sides of the sheet, said corrugations running in a direction non-perpendicular to said longitudinal edges whereby to provide mechanical resistance to separation by slipping one over 10 the other in a direction perpendicular to the 15 said longitudinal edges.
2. A paper receptacle including a body formed of a sheet of material shaped to tubular form and having its longitudinal edges 20 lapping and provided on their confronting faces with adhesive, said lapping edges being corrugated with a series of narrow and equal 25 corrugations symmetrical on opposite sides of the sheet, said corrugations running in a direction parallel to said longitudinal edges to provide mechanical resistance to lateral slipping and to increase the adhesive area.

Signed at New York city, N. Y., on October
30 31, 1927.

EDWARD C. ANGELL.
